CLAIM

The ornamental design for a container, as shown and described.

DESCRIPTION

FIG. 1 is a perspective view of a container showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of a container according to a second embodiment; and,

FIG. 9 is a front perspective view of FIG. 1, showing the lid in a partially open position.

The broken lines shown represent unclaimed subject matter and form no part of the claimed design.

The stippled shading shown in FIG. 8 represents a surface texture and forms part of the claimed design.
